(57) **CLAIM**

The ornamental design for a food utensil as shown and described.

DESCRIPTION

FIG. 1 illustrates a view of the food utensil;

FIG. 2 illustrates a left side elevational view of the food utensil;

FIG. 3 illustrates a right side elevational view of the food utensil;

FIG. 4 illustrates a front elevational view of the food utensil;

FIG. 5 illustrates a rear elevational view of the food utensil;

FIG. 6 is a top planar view of the food utensil;

FIG. 7 is a bottom planar view of the food utensil; and,

FIG. 8 is a view of the food utensil when in tension.

The broken line portions of the drawings are for illustrative purposes only and form no part of the claimed design.
